UNITED STATES PATENT OFFICE.

GUSTAF SELANDER, OF CHICAGO, ILLINOIS.

POKER AND CLINKER-EXTRACTOR.

1,324,986.

Specification of Letters Patent. Patented Dec. 16, 1919.

Application filed April 12, 1919. Serial No. 289,606.

To all whom it may concern:

Be it known that I, GUSTAF SELANDER, a citizen of the United States of America, and a resident of Chicago, in the county of Cook,

5 State of Illinois, have invented certain new and useful Improvements in Pokers and Clinker-Extractors, of which the following is a specification.

This invention relates to that class of implements in which means are provided in connection with a fire poker for engaging and extracting clinkers from the burning fuel of stoves and furnaces, and has for its object:—

10 To provide a simple and efficient structural formation and association of parts, wherein the clinker engaging means is attached to the shank of a poker in a pivotal and sliding manner, so as to be capable of 15 convenient manipulation in engaging and extracting a clinker from the fire, and which when not required for use can be retracted and held in an inactive condition with the point portion of the poker shank left in an 20 unimpeded condition for poking or stirring the fire, all as will hereinafter more fully appear.

In the accompanying drawing:—

Figure 1, is a perspective view showing 30 the clinker engaging bar in an active position for engaging a clinker.

Fig. 2 is a side elevation, showing the clinker engaging bar in its retracted position.

35 Fig. 3, is a front elevation of the same.

Like reference numerals indicate like parts in the several views.

Referring to the drawing, 1 designates the shank portion of a poker of the usual 40 straight form, formed at one end with a suitable point 2, at its other end with an operating handle 3 of any usual form, and with a cross-pin 4 intermediate its length as shown.

45 5 designates a sleeve or tubular head slidably mounted on the poker shank 1 and provided with lateral pivot ears 6, and with notches 7 at one end for engagement with the cross-pin 4 of the poker shank aforesaid.

50 8 designates a carrier bar preferably of a concavo-convex form in cross-section, arranged at the side of the poker shank 1 and having pivotal attachment at one end to the pivot ears 6 of the slideable sleeve 5 aforesaid by the usual pivot pin.

55 9 designates a laterally displaced portion

of the carrier bar 8, formed adjacent to the pivot end of the same to constitute a hand grip for the operator in the practical use of the implement.

10 60 designate one or more cross-heads fixedly attached to the free end of the carrier bar 8 and provided with prongs or claws 11 at their respective ends for holding engagement with a clinker.

12 65 designates a saddle head or member fixedly secured to the carrier bar 8 intermediate its length and provided with notches 13 adapted for engagement with the cross-pin 4 of the poker shank aforesaid.

When it is desired to use the present implement as an ordinary fire poker or stirrer, the carrier head 8 is slid back upon the poker shank 1 toward the handle 3, with the notches 13 of the saddle member 12 in engagement with the cross-pin 4 of the poker shank, to secure the parts closely together and so that said carrier bar 8 and its clinker engaging parts will not interfere with the use of the poker shank to stir the fire.

When a clinker is to be extracted from the fire, the carrier head 8 is swung away from the poker shank 1 a proper distance, and is then slid along the poker shank until the notches 7 of the head 5 are in engagement 85 with the cross-pin 4 aforesaid. After which the implement is moved to embrace the clinker and then the carrier bar 8 is closed by hand upon said clinker with the claws 11 in holding engagement therewith, and so

90 that the implement with the held clinker can be withdrawn from the fire with ease and certainty. In either of the above described uses of the implement, the hand grip portion 9 affords a convenient hold for one 95 hand of the operator in holding and manipulating the implement.

Having thus fully described my said invention what I claim as new and desire to secure by Letters Patent, is:—

100 1. In an implement of the type described, a poker shank, a head slidably mounted on said shank, and a carrier bar pivotally attached at one end to said head and provided with clinker engaging claws at the other end, 105 substantially as set forth.

110 2. In an implement of the type described, a poker shank, a head slidably mounted on said shank, means for limiting the movement of said head on said shank, and a carrier bar pivotally attached at one end to said head and provided with clinker engaging

claws at the other end, substantially as set forth.

3. In an implement of the type described, a poker shank provided with a cross-pin intermediate its length, a head slidably mounted on said shank and provided with lateral pivot ears, a carrier bar pivoted at one end to the pivot ears of the head aforesaid and provided intermediate of its length 10 with a saddle member having a notch in one end, and a cross-head secured to the free end of said carrier bar and provided with clinker engaging claws, substantially as set forth.
- 15 4. In an implement of the type described, a poker shank provided with a cross-pin intermediate its length, a head slidably mounted on said shank and provided with lateral pivot ears, a carrier bar pivoted at one end to the pivot ears of the head aforesaid 20 and provided intermediate its length

with an offset handgrip portion and with a saddle member having a notch in one end, and a cross-head secured to the free end of said carrier bar and provided with clinker 25 engaging claws, substantially as set forth.

5. In an implement of the type described, a poker shank provided with a cross-pin intermediate its length, a head slidably mounted on said shank and provided with 30 lateral pivot ears, a carrier bar of a concavo-convex form in cross-section pivoted at one end to the pivot ears of the head aforesaid and having a saddle member intermediate its length, and a cross-head secured to the 35 free end of said carrier bar and provided with clinker engaging claws, substantially as set forth.

Signed at Chicago, Illinois, this 9th day of April, 1919.

GUSTAF SELANDER.
